UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

LAMP-SOCKET.

1,378,467.

Specification of Letters Patent. Patented May 17, 1921.

Application filed January 9, 1915. Serial No. 1,337.

To all whom it may concern:

Be it known that I, CHARLES J. KLEIN, a citizen of the United States, residing at Milwaukee, in the county of Milwaukee and State of Wisconsin, have invented new and useful Improvements in Lamp-Sockets, of which the following is a full, clear, concise, and exact description, reference being had to the accompanying drawing, forming a part 10 of this specification.

This invention relates to electric lamp sockets.

One of the objects of the invention is to simplify the construction of lamp sockets 15 and reduce the manufacturing cost thereof.

Another object is to provide an improved lamp socket having a unitary casing to receive an insulating base and conducting shell through its open end and having automatic means to releasably support the in- 20 cased parts when inserted.

A further object is to provide an improved and simplified lamp socket of the type having a push button operated switch 25 mechanism.

Other objects and advantages will appear hereinafter.

The accompanying drawing illustrates certain typical embodiments of the invention 30 and depicts in,

Figure 1, an exploded elevational view of a lamp socket.

Fig. 2, an elevational view of the socket casing at right angles to the same shown in 35 Fig. 1.

Fig. 3, a plan view of the switch supporting base with a detail of the switch.

Fig. 4, an elevational view of the casing insulating lining at right angles to the same 40 shown in Fig. 1.

Fig. 5, an elevational view partially in section of the assembled socket disposed within a fixture husk.

Fig. 6, a side view of a modified socket of 45 a keyless type.

Fig. 7, a shadow view of the incased parts of Fig. 6.

Fig. 8, a sectional view of a further modified form of keyless socket, and

50 Fig. 9, a sectional view on the line 9—9 of Fig. 8.

Referring more specifically to the drawing, there are shown in Fig. 1 a unitary metallic casing A, a fiber insulating disk B,

a screw shell- and socket-supporting base 55 C, and a fiber sleeve D to line the casing A and to function as hereinafter set forth.

The casing A, as illustrated, comprises a one piece metal drawing having a substantially cylindrical body portion 1 with spaced 60 beads 2, 3, oppositely disposed switch button apertures 4, and having a contracted end portion 5 to which is secured a threaded bushing 6 for attaching the socket to the fixture and for accommodating the current 65 supply wires. The casing thus possesses increased rigidity and strength since its integral structure eliminates the separable and weak connection between the sections of multi-part casings. Furthermore, its manu- 70 facture is simplified since all sectional interlocking means are also eliminated.

The insulating disk B comprises an apertured dome portion having a marginal flange 7 and is adapted to line the casing end 5 75 with said flange abutting an interior ledge 8. The part C constituting the works of the socket includes an insulating base 9 which carries a conducting screw shell 10 and a switch mechanism having a reciprocable operating member 11 with detachable push buttons 12 and 13. Terminal binding posts 14 are arranged on opposite sides of the base below grooves 15 in an insulating base 16 which covers the switch mechanism. Said 85 base 16 has also an integral marginal flange 17 cut away at the grooves 15 and provided with rectangular lugs 18 above the push buttons. The fiber sleeve D is of a diameter to encircle snugly the works C and thus impose an insulating barrier between the metal casing and the metal socket parts. Marginal slots 19 are provided on opposite sides of the sleeve D to accommodate the switch push buttons 12, 13 and the base projections 18. 95 At right angles to said slots, integral lugs 20 are also provided to fit the cut away portions of the base flange 7, so that said base is supported by and held against rotation relative to the sleeve. 100

The casing A is adapted to receive through its open end the disk B, the works C and the sleeve D; the switch push buttons 12 and 13 being temporarily removed for this purpose. Moreover, the incased parts 105 are all supported against displacement within the casing through the medium of an automatic interlock between said casing and

the sleeve. As illustrated this interlock is effected between a resilient catch 21 and the casing walls about an aperture 22 provided in the casing bead 2. Said catch is preferably arranged at the lower extremity of a metal stamping 23 attached to the insulating lining D by any suitable means. In Fig. 4 the stamping is shown as provided with an open slot coinciding with one of the key 10 slots 19 in the sleeve and with inturned lugs 24 to abut the sides of said slot. A band 25 is wrapped about the lining and clamps the stamping 23 thereto by its ends 26 which are overturned through slots 27. As both the 15 stamping 23 and the band 25 are of thin metal the gross thickness of the insulating lining is not noticeably increased.

When the parts are assembled it is apparent that the base 16 supports the disk 20 B, the sleeve D and its parts support the works C, and the catch 21 automatically interlocks with the cut edges about the casing opening 22 to lock all the incased parts both against removal from and relative rotation 25 within the casing A. The presence of the insulating lining D is thus insured. The push buttons 12 and 13 are then insertable through the casing apertures 4 for connection with the switch member 11. While, of course, said push buttons might 30 be utilized to hold the incased parts against relative rotation I prefer to attain this result by the interlock described which maintains said buttons out of contact with the 35 sides of the apertures 4 and thus avoids any wear between the same.

The push buttons 12, 13 are preferably provided with reduced shanks 28 and 29 respectively which fit within resilient split 40 clamping fingers 30 and 31 integral with the switch actuating part 11. Said clamps 30 and 31 are also provided with indented lugs 32 for snapping into circumferential grooves 33 in the push button shanks and 45 thus detachably holding these parts together. Furthermore, as the push buttons are commonly colored distinctively to visually indicate the circuit condition of the switch mechanism I preferably make the 50 push button shanks 28 and 29 of unequal diameters and the clamps 30 and 31 of corresponding diameters, so that each push button will accurately fit only one end of the switch actuating member and incorrect attachment 55 of the push buttons is thus insured against.

In connecting the socket to a fixture within a husk 34 (Fig. 5), the casing may be first screwed to the fixture nipple and there- 60 after incased parts C and D readily inserted through the open end of the casing. The push buttons 12 and 13 may then be laterally inserted through suitable apertures in the husk and the casing apertures 4. Separation 65 of the parts similarly may be readily

effected by removal of the push buttons and disengagement of the catch 21 from the casing aperture 22. It is to be noted that the location of said interlocking parts adjacent the open end of the casing renders the 70 same easily accessible for disengagement. It is also to be noted that the wiring of the device is simplified since the unitary casing enables complete withdrawal of the socket parts and complete exposure of the binding 75 posts with minimum effort and delay.

In the form of device shown in Figs. 6 and 7, the lamp socket is without a switch mechanism and accordingly is of decreased longitudinal dimension. The insulating lining D in this form is provided with a metal stamping 35 which carries at its extremity the yieldable catch 21 but which is secured to the sleeve by integral extensions 36 arranged over the upper sleeve margin 80 and reflexed through slits 37 thereof. A narrow ribbon 38 of insulating material is placed within the upper end of the sleeve for covering the interior portions of the stamping 35 to insure against contact between said stamping and any current conducting socket parts. In this form also the casing and incased parts are provided with a multi-catch interlock comprising a plurality of the apertures 22 in the casing bead 95 2, into any one of which the catch 21 is adapted to snap. Thus the rotary positioning of the incased parts may be readily altered if desired without disturbing the attachment of the casing to the fixture. 100

The socket shown in Fig. 8 utilizes a molded insulation block 39 to inclose the screw shell 10 and support the socket terminals. Thus a separate insulating lining for the casing is rendered unnecessary and the interlocking means to support the incased parts are arranged between the open end of said casing and said molded block 39. As illustrated the casing is provided with oppositely disposed portions 40 slightly inturned below 105 short cuts in the metal and having their extremities disposed in opposite directions. The insulating base 39 is likewise provided with limited recesses 41 on opposite sides to receive said casing lugs 40 whereby the incased parts are held against withdrawal and relative rotation. To facilitate assembly the upper margin of the block 39 is beveled as at 42 directly above the recesses 41 so that the inturned lugs 40 are automatically expanded when the base is properly aligned and telescoped within the casing. It may be noted that this form of the device is particularly applicable for use under severe 110 conditions since the same is thoroughly 115 weather proof. 120

In each of the embodiments of the invention shown, the casing bushing 6 is provided with an encircling collar 43 having interior projections 44 which radially indent the 130

tapered walls of the bushing as the casing is attached to the fixture. Thus the socket may be locked in any desired rotary position for rendering the push buttons freely manipulatable.

What I claim as new and desire to secure by Letters Patent is:—

1. In a lamp socket, the combination with a substantially cylindrical inclosing shell contracted at one end, of a lamp socket fitting insertible in said shell through the open end thereof, one of said elements having a resilient catch to coöperate with a shoulder on the other for locking of said elements in assembled relation and against relative rotation and said catch having a part adjacent to the open end of said shell whereby it may be actuated to release said fitting.
2. In a lamp socket, the combination with a substantially cylindrical inclosing shell contracted at one end, of a screw-shell lamp socket fitting insertible in said shell through the open end thereof and means, including an insulating sleeve insertible between said fitting and said inclosing shell, to secure the former within the latter and to further secure the former against rotation relative to the latter, said sleeve being separable from said fitting.
3. In a lamp socket, the combination with a substantially cylindrical inclosing shell contracted at one end, of a screw shell lamp socket fitting and an inclosing insulating sleeve therefor, said fitting and said sleeve being insertible in said shell through the open end thereof and a spring catch fixed to said insulating sleeve and coöperable with a shoulder on said shell to support said sleeve and fitting in said shell, said catch being interposed between said sleeve and said shell and having a part adjacent to the open end of the latter whereby it may be actuated for disengagement from the shoulder of said shell.
4. In a lamp socket, the combination with a screw shell lamp socket fitting, of an insulating sleeve to surround and support said fitting and to interlock therewith for prevention of relative rotation, a spring catch fixed to said insulating sleeve exteriorly thereof, and an inclosing shell to receive said fitting, said sleeve and said catch having a shoulder to be engaged by the latter to lock said elements therein and to lock said sleeve against rotation within said shell, said catch having a part adjacent to the open end of said shell whereby it may be actuated for disengagement from said shoulder.
5. In a lamp socket, the combination with a substantially cylindrical inclosing shell contracted at one end, and provided with diametrically opposed openings, of a lamp socket fitting including a switch mecha-
- nism having axially alined detachable push buttons, said fitting upon detachment of said push buttons being insertible in the open end of said shell and means to lock said fitting within said shell but only when 70 in a given relation thereto whereby the push buttons may be inserted through said openings of said shell and attached to said fitting.
6. A push button operated switch for in- 75 closure in lamp socket shells and the like, comprising a switch mechanism including a reciprocable member, and a push button for actuating said member, one of the last two mentioned elements having resilient 80 parts to grip the other and permitting attachment and detachment of said push button by push and pull movements respectively.
7. A push button operated switch for in- 85 closure in lamp socket shells and the like, comprising a switch mechanism including a reciprocable member, and a pair of opposed push buttons for actuating said member, said member having spring parts to 90 grip said push buttons and permitting attachment and detachment of the latter by push and pull movements respectively, said gripping parts insuring against reversal of said push buttons relative to said member. 95
8. In a lamp socket, the combination with an integral inclosing shell substantially closed at one end and having its opposite end open, of a lamp socket fitting having an insulating base, screw-shell and center contact, lamp terminals mounted on the sides of said base, and a single piece insulating sleeve surrounding and inclosing said screw shell and the portion of said base carrying said wire terminals, said fitting and said 100 sleeve being insertible through the open end of said shell.
9. In a lamp socket, the combination with an inclosing shell, of a switch mechanism including a member adapted to be reciprocated for operation of the switch and having its extremities terminating within the contour of said switch mechanism and a push button for actuating said member, said member and said button having parts 110 115 adapted to resiliently interlock for permitting attachment and detachment of said push button and said member by push and pull movements respectively of the latter, and means independent of said latter mentioned parts for releasably securing said switch mechanism within said shell while relieving said parts of the support of said switch mechanism.
10. In a lamp socket, in combination, an 125 insulating base having external conductor grooves extending longitudinally thereof and transversely extending shoulders between said grooves, screw shell and center contact lamp terminals fixed to one end of 130

said base, wire terminals fixed to the sides of said base adjacent to said grooves and an insulating sleeve surrounding and inclosing said screw shell and the portion of 5 said base carrying said wire terminals, said sleeve abutting said shoulders on said base.

In witness whereof I have hereunto sub-

scribed my name in the presence of two witnesses.

CHARLES J. KLEIN.
